Patented Oct. 15, 1963

196,588

TELEVISION ANTENNA

George B. Poliakoff, 1 Park Circle, Great Neck, N.Y.

Filed June 11, 1963, Ser. No. 75,307

Term of patent 14 years

(Cl. D26—14)

FIG. 3

FIG. 4

FIG. 1 is a front elevation of a television antenna showing my new design,

FIG. 2 is a rear view of the television antenna,

FIG. 3 is a top view of FIG. 1 taken along lines 3—3, and

FIG. 4 is an enlarged side view with a portion of the antenna being broken away for convenience of illustration.

I claim:

The ornamental design for a television antenna, substantially as shown and described.
